UNITED STATES PATENT OFFICE.

WALTER S. KILLAM, OF DETROIT, MICHIGAN.

PRIMING DEVICE.

Application filed October 8, 1921. Serial No. 506,260.

To all whom it may concern:

Be it known that I, WALTER S. KILLAM, a citizen of the United States of America, residing at Detroit, in the county of Wayne 5 and State of Michigan, have invented certain new and useful Improvements in Priming Devices, of which the following is a specification, reference being had therein to the accompanying drawings.

- 10 This invention has special references to that class of priming devices which are mounted on the cylinder block of an internal combustion engine and are adapted to communicate with the cylinders or combustion chambers of the engine to permit of gasoline, kerosene or other fuel entering the cylinders or combustion chambers for priming or starting purposes. Such devices, especially those attached to engines of the V type 15 or cylinders which are angularly disposed, include angular supports and valvular cups, the supports maintaining the cups in vertical planes so that a priming agent can be readily placed in the same. The supports 20 have passages and the cups screwthreaded ported stems terminating in needle valves movable to and from the outer ends of the support passages, whereby the cups may be adjusted by rotation to close or open the 25 passages of the supports. The supports are subjected to vibrations which tend to loosen the cups and unseat the valvular ends thereof, and in consequence of this accidental or unknown adjustment of the priming cups 30 the combustion chambers or cylinders are open to the atmosphere and compression within the cylinders is materially interfered with and the efficiency of the engine decreased.
- 35 My invention aims to provide positive and reliable means, in a manner as hereinafter set forth, for clamping, securing or locking a priming cup against accidental adjustment after it has been set in a defined position, and the means which I employ does not alter the priming cup or materially change the design of the cup support. Instead, my invention lends a distinct advantage to the valvular priming cup, and the construction 45 by which I obtain the above and other results will be hereinafter described and then claimed.
- 50 Reference will now be had to the drawing, wherein
- 55 Figure 1 illustrates, in elevation, angular priming devices mounted in the cylinder

blocks of an internal combustion engine of the V-type;

Fig. 2 is a vertical sectional view of a priming device in accordance with my invention,

Fig. 3 is a horizontal sectional view taken on the line 3—3 of Fig. 2, and

Fig. 4 is a central axial section of the priming cup in a plane transverse to the section shown in Fig. 2.

The priming device comprises an angular support 1 having a nut portion 2 and a threaded portion 3 which permits of the lower angular end of the support being 70 mounted in the wall of a combustion chamber or cylinder of an engine 4^a. The angularity of the support 1 is such that the upper end of the support will be retained in a vertical plane irrespective of the angularity 75 of the combustion chamber or cylinder of the engine 4^a, and the upper end of the support has a chamber 4 communicating with a longitudinal passage 5 in the support 1. The juncture of the passage 5 with the chamber 4 affords a valve seat 6 and the walls of the chamber 4 are screwthreaded to receive the threaded portion 7 of a cup stem 8. The inner end of the cup stem 8 is of less diameter than the chamber 4 and said stem terminates in a needle valve 9 provided with ports 10 communicating with a bore 11 of the stem 8. The outer or upper end of the stem 8 has a conventional form of knurled cup 12 adapted to hold a small quantity of 80 priming agent, and said cup serves as a hand piece for adjusting the needle valve 9 relative to the valve seat 6. With the needle valve 9 closed the passage 5 is closed and the combustion chamber or cylinder of the 85 engine sealed relative to the priming device. With the needle valve 9 open any priming agent placed in the cup 12 may flow through the bore 11 and the ports 10 into the chamber 4 and from said chamber through the passage 5 to the combustion chamber or cylinder of the engine.

100 So far I have described what I have believed to be a conventional and practical form of priming device, and as pointed out 105 in the beginning it is extremely difficult to retain the needle valve 9 closed due to vibrations of the support 1 when the engine is in operation. To positively hold the needle valve seated I construct the upper end 110 of the support 1 so that it may be clamped about the threaded portion 7 of the stem

8. The upper end of the support 1 is provided with a plurality of slits or slots 13 so that there will be a plurality of support portions which may be slightly sprung and frictionally clamped against the threaded portion 7 of the stem 8 to prevent accidental movement of the stem in the support. The upper end of the support is also exteriorly screwthreaded and provided with a nut or 10 rotatable locking member 14, there being a slight taper to the upper end of the support 1 and a corresponding taper in the nut so that by screwing the nut 14 on the upper end of the support the contractible portions of the support may be sprung against the threaded portions 7 to bind the threads to such an extent that the stem cannot accidentally rotate. When it is desired to 15 unseat the valve of the stem it will be necessary to loosen or unscrew the nut 14 to such an extent that the cup 12 may be rotated to raise the valve 9 from the seat 6.

It is thought that the utility of my improvement will be apparent without further 25 description, and while in the drawing there is illustrated a preferred embodiment of my invention, it is to be understood that the construction is susceptible to such changes as fall within the scope of the appended claims.

30 What I claim is:—

1. In a priming device wherein a cup is supported in a vertical position and has a needle valve movable by rotation to and from an angular end of a longitudinal passage in a support for the cup and wherein

the needle valve controls the admission of a priming agent to the passage and is adapted to close the passage by seating on said support at the end of the passage therein:— means for holding said cup seated on said support against accidental unseating, said means comprising a rotatable nut engaging said support and by such engagement preventing accidental rotation of said cup. 40

2. A priming device as set forth in claim 1, wherein the support has exteriorly screwthreaded slotted portions which are contracted about a threaded portion of the cup by said nut. 45

3. The combination of an angle support having a longitudinal passage and valve seat, with the axis of the valve seat at an angle to the axis of the passage, said support being slotted and interiorly and exteriorly screwthreaded above its valve seat, a cup having a ported stem screwed in said support with the stem terminating in a valve adapted to engage the valve seat and shut off communication between said cup and the support passage, and a nut screwed on the slotted portion of said support and adapted to contract said support about the stem of said cup to hold the valve stem of said cup on the seat of said support. 50 55

In testimony whereof I affix my signature 60 in presence of two witnesses.

WALTER S. KILLAM.
